SCREEN DOOR GRILLE

Filed June 4, 1929

FIG. 1 FIG. 2

UNITED STATES PATENT OFFICE

HARRY J. LEBHERZ, OF FREDERICK, MARYLAND, ASSIGNOR TO THE EVEREDY COMPANY, OF FREDERICK, MARYLAND, A CORPORATION OF MARYLAND

SCREEN DOOR GRILLE

Application filed June 4, 1929. Serial No. 363,392.

My invention relates broadly to protective attachments for screens and more particularly to a construction of a grille adapted for installation upon the frame of a screen for protecting the fine wire screen against injury.

One of the objects of my invention is to provide a construction of protective grille for screens by which the fine wire mesh of a screen may be protected against injury from obstructions and pressure brought to bear against the protective grille rather than against the fine wire mesh of the screen.

Another object of my invention is to provide a construction of attachable grille for screens with means by which the grille may be centered over that area of the fine wire screen mesh which it is desired to protect against injury.

20 A further object of my invention is to provide a self-sustaining grille which is attachable to the frame of a screen for protecting the screen against injury for safeguarding an entrance-way, the grille being supported 25 with respect to the screen from a multiplicity of positions on the frame of the screen.

A still further object of my invention is to provide a construction of grille for the protection of screens wherein the grille comprises a multiplicity of laterally and longitudinally extending strip members, interlaced or woven, electrically welded at their extremities with strengthening ribs outstruck from the strip members intermediate 35 the junctures with means for adjustably centering and supporting the grille with respect to the frame of the screen.

My invention will be more fully understood from the specification hereinafter following by reference to the accompanying drawings, in which:

Figure 1 illustrates the grille of my invention applied to the lower section of a screen door; Fig. 2 illustrates a modified 45 form of grilles structure of my invention applied to an intermediate section of the screen door; Fig. 3 is an enlarged fragmentary view of the grille of my invention showing one of the supporting means by which 50 the grille may be centered with respect to

the frame of the screen; Fig. 4 is a cross-sectional view through the grille structure on line 4-4 of Fig. 3; Fig. 5 is a cross-sectional view of one of the adjustable supporting means for the grille taken on line 55 5-5 of Fig. 3; and Fig. 6 is a cross-sectional view through the grille structure on line 6-6 of Fig. 3.

The grille of my invention finds particular application upon screen doors where it is desired to protect the fine wire mesh of the screen door against injury. The grille consists of a multiplicity of laterally and longitudinally extending strips which are electrically welded at their extremities and are each strengthened by an outstruck rib intermediate the junctures of the strips. The grille is provided with marginal supports, each of which have a portion thereof having a substantially tubular cross-section into which pin members are arranged to adjustably slide, which pin members are supported from the frame of the screen. By providing adjustable pin or rod members at each corner of the grille, it is possible to adjust the grille to screens of different sizes in order to properly center the grille with respect to the frame and the screen which is carried by the frame.

Referring to the drawings in more detail, reference character 1 designates a screen door having an upper screen section 2 and lower screen sections 3 and 4. The lower screen sections are protected against injury by the application of the grille 5 to the frame of the screen. The grille 5 as shown more clearly in Fig. 3 comprises a multiplicity of laterally extending strip members 6 and vertically extending strip members 7 which are woven or interlaced between a pair of marginal frame members 8 and 9. The marginal members 8 and 9 have a substantially tubular portion 10 into which rod members 11 project at each of the four corners thereof. The rod members 11 are each provided with flattened portions 12 which are secured by means of screw members 14 to the frame of the screen in that position by which the grille may be centered over the fine wire screen mesh. The laterally

and longitudinally extending strip members 6 and 7 are each provided with outstruck ribs 15 intermediate the junctures of the strips at 16 for the purpose of strengthening the grille. The junctures 16 are not mechanically connected, the strips being shaped to provide offset flattened portions at each of the cross-over points to permit the weaving or interlacing of the strips without displacement of the strips substantially out of alignment with the plane of the grille. The strips are maintained in position by connections at the extremities thereof. The flat faces of the strips abut with each other and their intersections, and by virtue of the inherent resiliency of the strips sufficient tension is made effective to secure the strips in substantially the same plane. The marginal members 8 and 9 each have parallel extending jaws which I have designated at 17 between which the ends of strips 7 project for the purpose of confining the vertically extending strips by a welding process rigidly to the marginal members 8 and 9. It will be observed that the strips 6 and 7 pass alternating above and below each other at the juncture positions in the nature of a woven or interlaced structure by which the grille structure is considerably strengthened.

The grille of my invention has been found to be extremely practical in its construction and successful in its use. The grille may be attached to screen doors or windows of various sizes and serves to protect the screen against the pressures to which the screen may be subjected in the normal wear and tear in the use of the screen door. The grille also provides safety means when applied to windows in protecting a screened entrance against the cutting away of the screen for the purpose of entry therethrough.

While I have described the grille of my invention, in certain of its preferred embodiments, I desire that it be understood that modifications may be made and that no limitations upon my invention are intended other than are imposed by the scope of the appended claims.

What I claim as new and desire to secure by Letters Patent of the United States is as follows:

1. A grille structure comprising a multiplicity of laterally and longitudinally extending strip members interwoven with each other in tensioned engagement at the junctures thereof, outstruck ribs formed in said strip members between the junctures thereof, laterally extending marginal members at the top and bottom of said grille, said marginal members receiving the ends of said longitudinally extending strips, a cylindrical recess in each of said marginal members and pin members projecting into the cylindrical recesses in said marginal members for fric-

tionally engaging the inner walls of the cylindrical recesses in said marginal members for supporting said grille structure.

2. In a grille structure, a multiplicity of strips extending substantially at right angles with respect to each other and interlaced, said strips resiliently engaging each other at the intersections thereof and provided with strengthening ribs intermediate said intersections, marginal members at opposite ends of the grille for receiving the ends of the strips which extend at substantially right angles thereto, tubular portions formed in said marginal members, and pins frictionally engaging the tubular portions of said marginal members for mounting said grille structure.

3. In a grille, a multiplicity of strips extending substantially at right angles with respect to each other and interlaced one with the other to form a multiplicity of sections, said strips being mechanically free from each other at each intersection but resiliently sprung together, means strengthening said strips intermediate the intersections thereof, a pair of marginal members at opposite ends of said grille, said marginal members each including portions which receive the ends of strips extending at right angles to the marginal members and being provided with tubular portions adjacent each corner of the grille, and adjustable pin members telescopically positioned within the tubular portions of said marginal members, for supporting said grille.

4. A grille comprising a plurality of laterally and longitudinally extending interwoven strip members, marginal members extending along two opposite edges of said grille, said marginal members each comprising a strip rolled into a tubular portion terminating in parallel extending jaws, said jaws engaging the ends of certain of said strip members, slidable members including a flattened attaching portion and a portion having a section corresponding to the section of said tubular portion of said marginal members adjustable to selected positions telescopically within the tubular portions of said marginal members at the opposite extremities thereof for supporting said grille in position.

In testimony whereof I affix my signature.

HARRY J. LEBHERZ. 120
